Inventor

Cyrus C. Clapp

United States Patent Office.

CYRUS C. CLAPP, OF HARTFORD, CONNECTICUT, ASSIGNOR TO HIMSELF AND R. M. BURDICK, OF SAME PLACE.

Letters Patent No. 69,770, dated October 15, 1867.

DEVICE FOR TURNING THE LEAVES OF BOOKS.

The Schedule referred to in these Letters Patent and making part of the same.

TO ALL WHOM IT MAY CONCERN:

Be it known that I, CYRUS C. CLAPP, of the city and county of Hartford, and State of Connecticut, have invented certain new and useful Improvement in Device for Turning Leaves of Books; and I do hereby declare that the same is described and represented in the following specification and drawings; and to enable others skilled in the art to make and use the same, I will proceed to describe its construction and operation by referring to the drawings, in which the same letters indicate like parts in each of the figures.

The nature of this improvement consists in simplifying the mechanism, so as to render it easier and cheaper of manufacture, and more convenient and desirable for use. In the accompanying drawings—

Figure 1 is a front elevation.

Figure 2 is an end view of the same.

Figure 3 is a top view.

Figure 4 is a back side view.

Figure 5 are views of detached portions of the mechanism.

a represents a book-rack, as in common use. *b* is the framework, in or to which the device is arranged. *c* are hooks, or other equivalent device, for securing or holding this improvement to the common rack for use. *d* is a book-holder. *e* is a plate, to which the mechanism is arranged. *f f* are groove-wheels, which are secured to and oscillate upon a fulcrum-pin or screw, *g*, between the studs *h*. *i i* are arms, for turning leaves of a book, which are secured to the edge of the wheels *f*. Just back of the arms *i* are arranged detents *i'*, by means of which said arms *i* are held back in readiness for action. *i'' i''* are elastic cords, one end of which is secured in the groove edge of the wheels *f*, while the other has a knot tied at any desired point at or near the end thereof, which is held securely by placing said knot in one of the slits of the rack *j*. *p p* are dogs, arranged between studs upon the back side of the plate *e*, having springs *q* for holding their front ends closely against the edge of the wheels *f*. *k* is a sliding-plate, having a finger-knob, *m*, ratchet *n*, and a protuberance, *o*, which extends back so that when the slide is moved up or down said protuberance acts to lift the front end of the dogs *p* from the detents *i'*, (one at a time,) and allow the arms *i*, (held back by said dogs *p*,) by the action of the elastic cords *i''*, or their equivalents, to be thrown forward from right to left. Said plate *k* is arranged just at one side of and at right-angles with the wheels *f*. *r* is a pedal, secured upon a shaft, *s*, which has its bearings in the posts *s'*. On the outer end of this shaft *s* is secured an arm, *t*, having an angle pawl, *u*. This pawl is held up to and works in the ratchet *n* (by a spring, *u'*), to disengage the detent *i'* from the dogs *p* in the edge of the wheels *f*. The rack end of said pawl is provided for the purpose of lifting the pawl from the ratchet *n*, when it is desirable to return it (the ratchet) to its starting or resting place, which may be done by pressing at the same time the rack end of the pawl and the knob *m*, when the arms (when turned back from left to right) will be in readiness to turn a leaf, when desirable. The book-holder *d* is made in spring form, the end of which extends upward through a slit in the upper side of the framework, so as to allow it to move back and forth to receive a book or music-sheet. Said spring or holder is or may be made either in one or two pieces, as desirable, so as to allow it to be attached or detached at pleasure. *x* is a pad, for the arms *i* to strike against, as they fly back from right to left, or from one side to the other.

Now it will be readily seen that the frame *b* can be easily and quickly attached and detached to or from the common book-rack, when desirable, by means of hooks *c*, or their mechanical equivalents; also, that by bearing down the rack end of the pawl *u*, and at the same time pressing down the plate *k* by its knob *m*, and then turning the arms *f* back from left to right, and then engaging the clips *l* to the leaves of a book, they may be quickly and successively turned, as desirable, by simply pressing the pedal *r*.

The clips *l* are secured loosely to the end of the arms *i* (which are provided with two or more holes, *2*, near their outer ends) by means of an elastic cord, *3*, passing through said holes, so as to allow of its being lengthened or shortened, as may be desirable, simply by pulling the cord. Directly under the back end of the pedal-lever is arranged a pad, *2'*, for the said lever to rest upon as it is reacted by the spring *y* arranged upon the shaft *s*.

I believe I have thus shown the nature, construction, and advantage of this improvement, so as to enable others skilled to make and use the same therefrom.

What I claim, therefore, and desire to secure by Letters Patent, is—

1. I claim, in a leaf-turning device, the combination of the pedal *r*, shaft *s*, arm *t*, spring-pawl *u*, ratchet *n*, for holding or releasing the wheels *f*, substantially as described.
2. I claim the clips *l*, with the cord *3* secured loosely in the holes *2* of the arms *i*, substantially as and for the purpose described.

CYRUS C. CLAPP. [L. S.]
